COMBINED BED-READING LAMP AND
CLOCK

Eugene J. Springer, Philadelphia, Pa.

Application May 12, 1941, Serial No. 393,111

4 Claims. (Cl. 240—4)

The present invention relates to a certain new and useful bed-reading lamp and clock.

An object of the present invention is to provide a device which is adapted to furnish illumination for a person in a reclining position and at the same time to provide, as an integral part thereof, time-indicating means whereby the person can quickly and easily determine the time without having to stretch himself or otherwise to change his position or to strain his eyes in attempting to read a relatively remote and poorly visible clock.

Another object of the present invention is to provide a combination bed-reading lamp and clock which is simple, inexpensive and efficient and which will furnish illumination for a person reading in bed and, at the same time, enable him quickly and easily to determine the time.

Still another object of the present invention is to provide a combination bed-reading lamp and clock in which the clock is illuminated or otherwise made visible to permit its being seen in the dark.

In the past, it has been known that a person attempting to read in bed has found it inconvenient and indeed difficult to determine the time. Thus, if a person reading in bed by means of an ordinary bed lamp or a table lamp desires to tell what time it is, it is necessary for him to lift himself up and to turn his body and head in order to look at a clock which is usually upon the table or other piece of furniture in the room. This lifting and turning involves appreciable effort and strain and, in addition, the clock is usually outside of the range of the reading lamp so that its face is poorly visible, if it can be seen at all.

While, in the case of a physically able person, such lifting and turning involves discomfort and is generally undesirable, in the case of a person who is an invalid or a patient in a hospital or is otherwise incapable of moving himself such lifting and turning would be utterly out of the question.

My present invention solves this problem by providing a simple and inexpensive bed reading lamp and clock by means of which a person reading or otherwise using his eyes in bed is enabled to tell the time quickly and easily without any movement of his body whatsoever.

For the purpose of illustrating the invention, there are shown in the accompanying drawings forms thereof which are at present preferred, since the same have been found in practice to give satisfactory and reliable results, although

it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

Figure 1 represents a perspective view of one embodiment of the present invention as it appears in use; the case 10 being shown in a phantom view to reveal the clock face 26 at the under-side of said case.

Figure 2 represents a vertical cross-sectional view of the embodiment shown in Figure 1.

Figure 3 represents a bottom elevational view of the embodiment shown in Figures 1 and 2 as it would normally appear to one using it.

Figure 4 represents a perspective view of another embodiment of the present invention; parts being broken away better to show the construction thereof.

Figure 5 represents a bottom elevational view of the embodiment shown in Figure 4 as it would appear to one using it.

Figure 6 represents a vertical cross-sectional view along the line 6—6 of Figure 4.

Figure 7 represents a fragmentary bottom elevational view of one embodiment of the present invention illustrating one method of illuminating the face of the clock.

In the embodiment shown in Figures 1, 2 and 3, I may provide a case 10 having a lens 12 therein. Said lens 12 may be of glass or other transparent material. Said lens 12 may be of plane glass so as merely to transmit light from the interior to the exterior of the case 10 or said lens 12 may be made in the form of a convex lens to focus the light from the interior of the case 10 upon a relatively limited field exterior thereto.

Within said case 10, I may provide any suitable source of illumination, as for example an ordinary electric light bulb 13 which may be inserted into an ordinary electric light socket 14, which in turn is supported within said case 10 in any suitable manner.

An electric light cord 15 is connected to said socket 14 and extends outwardly through an opening 16, preferably in the rear of said case 10 and is adapted to be plugged into an electric power line in the usual manner.

A switch 17 of any conventional construction is provided upon the exterior of said case 10 for turning said bulb 13 on and off.

A clock which is indicated generally by the numeral 18 is provided within the lower portion of said case 10. Said clock 18 may be electrically operated by means of any conventional electric motor as for example the synchronous motor 19 which may be connected to the electric cord 15.

In place of the electric clock shown in Figures 1, 2 and 3 it is possible to use a spring-driven clock of conventional construction or an electrically-wound spring-driven clock of conventional construction.

Said clock 18 may be disposed within the lower portion of said case 10, as hereinabove described, with its face 20 directed downwardly at the bottom of said case 10. Said face 20 is so positioned that it may be read by a person who is lying in bed by merely raising his eyes and looking upwardly.

Said face 20 is provided with numerals 21 and 20 with time-indicating hands 22.

Said face 20 is preferably made of transparent or translucent material and is so positioned that it is illuminated from within by said bulb 13 so that it is readily visible to the person lying in bed.

Said face 20 may be of "frosted" glass or colored glass, or plastic or other suitable material with the numerals 21 and the hands 22 of contrasting appearance, so that when said face 20 is illuminated from within, the numerals 21 and the hands 22 will be clearly visible to the person reading in bed.

Instead of having the entire face 20 of translucent or transparent material, it is possible to have the main portion of the face 20 opaque with the numerals 21 transparent or translucent and with means for illuminating the hands 22; as for example, by having a generally annular slit 34 formed upon the face of a clock as shown in Figure 7.

Thus, as shown in Figure 7, the face 20-a may be provided with numerals 21-a which are transparent or translucent to permit the passage of light therethrough or which may simply be cut out of the face 20-a and an hour hand 22-a and a minute hand 22-b which may be opaque.

A generally annular slit or opening 34 may be formed upon the face 20-a radially inward of the numerals 21-a. Said slit 34 may be transparent or opaque or may simply be an opening cut out of the face 20-a. If said slit 34 is an opening, small bridging portions 44 may be provided to connect the radially outer and inner portions of the face 20-a.

Said slit 34 is so placed that the outer tip of the hour hand 22-a coincides therewith while the minute hand 22-b extends radially outwardly beyond said slit 34.

Thus, a person looking at the clock in a generally dark room is enabled to tell the time at a glance since the numerals 21-a will be illuminated from within the clock and since the positions of the hour and minute hands 22-a and 22-b can be seen against the illuminated strip 34.

The case 10 may be provided with openings 11 to permit ventilation thereof and thus prevent a rise in temperature as might affect the working of the clock 18.

Instead of having the clock 18 in the same compartment with the bulb 13, it is possible to have said clock 18 in a separate compartment so that the clock will be further protected from 75

the heat of the bulb. Where this is done, the partition separating the clock from the bulb may be transparent to permit the light from the bulb 13 to pass through the partition to illuminate the face 20 of the clock 18 or the partition may be opaque and a separate small bulb may be provided within the compartment containing the clock 18 to illuminate the face 20 from within.

The bed reading lamp and clock of the present invention may be provided with a ball-and-socket joint 35 to permit universal movement thereof and thereby to make said bed reading lamp and clock readily adjustable.

The bed reading lamp and clock of the present invention may be affixed to any suitable support as for example the headboard 30 of a bed 31 in any suitable manner; as for example by means of a C-clamp 32 and a bolt 33 screw-threadedly disposed within said C-clamp 32 and adapted to be adjusted to grip the head-board 30.

The bed reading lamp and clock of the present invention may also be constructed as an integral part of the head-board of a bed to provide a neater and more attractive appearance.

Another embodiment of the present invention is shown in Figures 4, 5 and 6. In this embodiment, I may provide a case 23 which is generally elongated having an elongated lens 25 therein.

A clock 26 which may be a spring-driven clock is provided within the lower part of the case 23 with its face 27 disposed upon the bottom surface of the case 23.

Said face 27 may be provided with numerals 28 and time-indicating hands 29.

A wind stem 36 may be provided adjacent to said face 27 for winding the clock 26 and for setting the hands 29.

A bulb 38 may be disposed within said case 23 preferably extending from side to side thereof. A heat-insulating partition 39 may be provided separating the bulb 38 from the clock 26 as shown particularly in Figure 6.

Projecting downwardly from the bottom of the case 23, I may provide a small bulb 40 for illuminating the face 27 of the clock 26. A shield 41 may be provided to reflect the light from the bulb 40 on to the face 27 of the clock 26 and to prevent the light from the bulb 40 from shining down into the eyes of the reader.

The bulbs 38 and 40 may be connected to a suitable electric cord 42 whereby they may be plugged into any suitable electric outlet. A switch 43 may be provided for turning said bulbs 38 and 40 on and off.

Said case 23 may be provided with a ball-and-socket joint and a C-clamp similar to that shown in Figures 1 and 2.

Instead of having the reading lamp and clock of the present invention affixed to the head-board of a bed it is possible to mount it upon a suitable pedestal so that it may stand upon the floor or upon a table or other suitable surface.

Instead of illuminating the face of the clock, it is possible to coat the time-indicating hands and the numerals with luminous paint to make them visible in the dark.

While the drawings show clocks having a dial face and time-indicating hands, it is possible to use any conventional drum-type clock in which the time-indicating numerals rotate past a time-reading opening.

It is possible to use any appropriate source of illumination as for example an incandescent light or a fluorescent light or to provide non-glare, polarized light by using a polarizing lens.

While, in Figure 6, the partition 39 may be opaque since the face 27 of the clock 26 is illuminated from without by the bulb 40, it is possible, and indeed it may sometimes be preferred, to make said partition transparent or translucent as well as heat-insulating so that the time-indicating face of the clock may be illuminated from within by the bulb 38 (or the bulb 43); in which case, of course, the bulb 40 may be dispensed with.

It is possible to provide the clock in my novel bed reading lamp and clock with an alarm so that it serves the additional function of awakening the sleeper in the morning.

While the drawings show means exterior to the case for setting the hands and winding the clock, it is possible to provide said setting and winding means within the case and to make the case in two or more parts or to provide the case with an opening therein so that access may be had to the interior of the case for winding or setting the clock.

It is also possible to construct my bed reading lamp and clock so that the clock may be removable therefrom as a unit and so that the clock may be used independently of the lamp if so desired.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

The invention having been hereinabove described, what is hereby claimed as new and desired to be protected by Letters Patent, is:

1. A reading lamp and clock comprising a case, means for positioning said case above and adjacent to the head of a reader, a source of illumination within said case, means for directing light from said source of illumination upon a book or the like, a clock disposed within said case and presenting a time-indicating face upon the under-side of said case, said time-indicating face being capable of transmitting light therethrough, and means for illuminating said time-

indicating face from said source of illumination.

2. A reading lamp and clock comprising a case, means for positioning said case above and adjacent to the head of a reader, a source of illumination within said case, means for directing light from said source of illumination upon a book or the like, a clock disposed within said case and presenting a time-indicating face upon the under-side of said case, said time-indicating face being adapted to transmit light therethrough, and a light-transmitting heat-insulating partition within said case separating said source of illumination from said clock whereby said time-indicating face will be illuminated by said source of illumination.
3. A reading lamp and clock comprising a case, means for positioning said case above and adjacent to the head of a reader, a source of illumination within said case, means for directing light from said source of illumination upon a book or the like, a clock disposed within said case and presenting a time-indicating face upon the under-side of said case, said time-indicating face being generally opaque, time-indicating numerals formed upon the outer periphery of said time-indicating face, a generally annular light-transmitting opening formed upon said time-indicating face radially inward of said time-indicating numerals, an hour hand operatively disposed upon the exterior of said time-indicating face having its outer end coinciding with said annular opening, a minute hand operatively disposed upon the exterior of said time-indicating face and projecting radially outwardly beyond said annular opening, and means for illuminating said time-indicating face from the back thereof.

4. A reading lamp-clock comprising a case, means for positioning said case above and adjacent to the head of a reader, a source of illumination within said case, means for directing light from said source of illumination upon a book or the like, a clock disposed within said case and presenting a time-indicating face upon the under-side of said case, and means for illuminating said time-indicating face from said source of illumination.

EUGENE J. SPRINGER.
